FIRE EXTINGUISHER

Joseph Coates Carter, Martinsville, Va.

Application January 5, 1942, Serial No. 425,684

9 Claims. (Cl. 169—32)

This invention pertains to a fire extinguisher that automatically releases gas to smother a flame.

It has been desirable to apply extinguishing sprays automatically. It is not always desirable to arrange an automatic extinguisher as part of a more or less permanent structure. Preferably, it is desirable to devise an arrangement that can be used either in a permanent structure or in a portable extinguisher. A purpose in this invention is to provide this adaptability readily. A need exists also for a simple arrangement of parts to be replaced after use of the extinguisher. A feature of the present invention is to utilize elements that are of themselves well known and usually available, but that may permit interchange of materials in the event that certain of the elements become unavailable for one reason or another.

A general purpose of this invention is to provide extreme simplicity of manufacture, and also to provide dependable and automatic operation when need exists for the extinguisher. Other objects of this invention will appear in the accompanying description.

In the accompanying drawing are shown illustrative embodiments, while the accompanying claims particularly point out novel features of the invention. The following description is illustrative of preferred practice that furthers the objects for which this invention is suited.

In the drawing:

Figure 1 shows in elevation part of a wall of the envelope of the extinguisher;

Figure 2 shows a vertical section through the extinguisher within the container shown in elevation in Figure 1;

Figure 3 shows a horizontal cross section of the extinguisher taken along the line 3—3 of Figure 2;

Figure 4 is a vertical section taken across the extinguisher along the line 4—4 of Figure 2;

Figure 5 shows in horizontal cross section analogous to Figure 3 a modified form of structure embodying this invention; and

Figure 6 shows in vertical section analogous to Figure 4 a further modified structure embodying the features of this invention.

According to preferred practice the objects of this invention are attainable by arranging a plurality of thin walls within an envelope to form a cellular structure, some of the cells containing reagent of one sort and the other cells containing reagent of another sort such that the two when intermixed yield flame-extinguishing gas.

The arrangement is such that on slight elevation of temperature these interior walls or some of them will fuse and the reagents in adjacent cells become intermixed automatically within the envelope and generate sufficient pressure for the gas to burst from the envelope.

Referring more particularly to the drawing illustrating specific preferred embodiments of this invention, the envelope 1 is of thin heat-conducting material such as thin sheet metal. Suitable material, for example, is such as currently is used to form cans. Within this envelope the space is divided into a plurality of cells by thin walls of fusible material, such as sheet lead or alloys thereof or of aluminum alloys. The materials suitable for such interior walls are many and are of themselves known to those skilled in the art as being fusible at slightly above normal temperatures. The materials, however, should possess sufficient strength to withstand ordinary handling. Some of these cells are filled with liquid and others are filled with solids or reagents of such nature as to react with the liquid to release flame-smothering gas. Some cells may be filled with acid and others may be filled with bicarbonate. These materials, however, are illustrative and are not limiting of this invention inasmuch as other materials suitable for the purpose are known to those skilled in the art.

A suitable disposition of reagents in the cells will be an alternate arrangement of liquid as in cells 2 and next of a solid as in cell 3. The resulting pattern is tessellated, such as illustrated in Figure 2. This shows in vertical section a liquid filled cell 2 above a solid filled cell 3 and that in turn above a liquid filled cell 2. In an adjoining column this arrangement is reversed so that the solid and liquid filled cells alternate in horizontal as well as in vertical rows. In this way if the walls between contiguous cells become softened sufficiently to yield, there will be at once an intermingling of acid and of solid. In practice this yield point may be confined to a small area initially, but if the temperature continues to rise may spread over considerable area. Thus if the area of rupture is slight the rate of intermixing of acid with solid will be correspondingly low. Thus an initial release of gas may be slight, but if the flame or heat requires a considerable release of gas then the rupture of walls will be considerable and the amount of gas formed will be correspondingly great.

The walls that fuse and weaken first may be those at the top and bottom of a cell or may be

those at the sides. These possibilities are illustrated in Figures 2, 3 and 4.

The initial disposition of heat applied to the extinguisher likewise may be understood from Figures 2, 3 and 4. As shown, the outer envelope is one of thin heat-conducting material. Consequently, heat is transmitted quickly to the interior cell walls, such as to the floor wall 5 of cell 2 illustrated in Figure 4. This heat flow will correspond to the demand; that is to say, correspond to the intensity of flame to be subdued and to its disposition near the extinguisher. In Figure 4 is illustrated an extinguisher that is relatively narrow, with side walls 1 of the envelope close together. Thus heat may be transmitted quickly from both side walls 1 to the floor wall 5 of cell 2 if the flame substantially surrounds this cell. On the other hand, if a flame is of such low intensity as to heat one wall, but not substantially to heat the other wall, the temperature of the floor wall 5 of the cell will rise primarily near the corner next to the flame. Thus in the first instance the whole floor 5 may weaken at once and acid may intermix quickly with a considerable amount of solid. On the other hand, where the weakening occurs only near one corner the passage of acid will be confined chiefly to that corner which is already weakened.

When gas is formed in the envelope, necessarily pressure rises within the envelope because of the impervious nature of the walls 1. This pressure may be made effective in various ways.

In the form of this invention illustrated in Figure 4 of the drawing, means to utilize pressure developed within the envelope comprise fusible plugs 6 as a part of the envelope wall 1. These plugs may be composed of material that weakens under the influence of heat as by fusion. For this purpose suitable materials will be known to those skilled in the art. Preferably such material for plugs 6 will weaken or fuse at a temperature somewhat higher than that of the cell walls 5. This is so that the cell walls may weaken first and generate a considerable pressure of gas before the release plugs 6 are caused to weaken. With such arrangement the gas spouts out with considerable force and spreads over considerable area at once. The bursting or blowing out of fusible plug 6 will be facilitated by the growing gas pressure within the corresponding cell. Thus with high heat and sudden generation of relatively large amount of gas, the plug will blow out very quickly. Preferably the retaining plugs 6 are disposed in alternate solid containing cells 3. The effect of this disposition is to permit considerable pressure to be built up by the time the plug 6 breaks. The plug nearest the demand is the first to release gas.

In modifications of this invention mechanical means to rupture the walls that separate a liquid cell 2 from a solid cell 3 may be provided. Such means are illustrated in Figure 6 by a pull wire 7 attached to interior cell wall 5. This arrangement is such that pull element 7 extends from its place of attachment to cell wall 5 through the mass of solid in cell 3 and through enveloping wall 1 to the exterior of the envelope. Thus element 7 may be pulled manually to tear back the cell wall 5 to permit mingling of acid with solid. In Figure 6 is illustrated only a single pull element 7, but it will be understood that such a disposition may be multiplied to rupture any cell walls.

In Figure 6 is illustrated further an advantageous structure to permit building up of pressure within a cell and then sudden release of the

gas therein. This arrangement comprises an automatic pressure-operated valve 8 that is inserted in envelope wall 1. Such pressure release valves are known of themselves and are of various types that may be selected by those skilled in the art. Such pressure release valves 8 may be used in conjunction with fuse plugs 6 or may be used as alternative thereto.

A further modification that may be used with the various forms of pressure release plugs or valves concerns an alternative disposition of the liquid reagent in capsules. Such a modification is shown in Figure 5. In Figure 5 is shown a series of liquid filled capsules 9 spaced apart and surrounded by a solid reagent that is simply packed or filled into the envelope 1. In Figure 5 these capsules 9 are illustrated as being cylindrical, but it is understood that under this invention these liquid filled capsules may be of any other shape. It will be understood further that either the cells or capsules may be of any suitable shape, such as cylindrical or hexagonal, as may be preferred for the purpose and under the requirements at hand.

It becomes evident from study of the advantages of this invention that in many instances an envelope will be used only partially. This would be the case where a small local fire weakens the walls of only a few cells and where the resulting gas pressure breaks only a few corresponding plugs 6 or else issues from only a few corresponding pressure release valves 8. Where only part of the cells are opened, the remaining structure is still usable and the parts already used may be replaced.

It will be observed further that an advantage of this invention resides in the possibility of replacing fusible plugs 6 in simple manner. Such plugs may be of a nature to be fused or to be cemented quickly into their respective openings in the envelope wall 1. As shown, plugs 6 are convex to be snapped into place. Thus in some instances repairs may be made to a fire extinguisher on the spot where it has been in use while in other instances repairs may be made readily to such extinguishers as have to be removed to some equipped location.

It will be apparent that a structure of the sort described herein may be adapted to various purposes. For example, extinguishers of the form illustrated and generally of rather thin rectangular form can be inserted into a wall; or several such elements may be piled around a small local fire and by their mere number and presence act as a baffle to exclude air from the burning material.

While I have in the above description disclosed what I believe to be a preferred and practical embodiment of the invention, it will be understood to those skilled in the art that the specific details of construction and arrangement of parts are subject to some latitude of variation without transcending the spirit and scope of the appended claims.

What I claim is:

1. A fire extinguisher comprising a cellular structure formed with thin walls of heat-conducting material the cell units containing separate reagents adapted to interact on contact with each other to form fire-smothering gas within the envelope, the envelope walls being adapted to rupture by heat and internal pressure and permit gas developed therein to spurt from the ruptured portion.
2. A fire extinguisher comprising a cellular

structure the cell units having low fusing wall portions and containing reagents to generate fire-smothering gas upon contact with each other within the structure.

3. A fire extinguisher comprising a cellular structure formed with walls provided with blow out portions the cell units having low fusing, wall portions containing reagents to generate fire-smothering gas upon contact with each other, the blow out portions of the envelope extending from individual cell units to permit escape of gas therefrom.

4. A fire extinguisher comprising a cellular structure formed with thin metal walls to facilitate rapid heating, some of the cell units therein containing liquid and adjacent cells containing solid reagents alternately for generating fire-extinguishing gas on intermixture of the liquid with the solid, the individual cell walls being fusible under heat to permit intermixture of the liquid with the solid.

5. A fire extinguisher comprising a cellular structure of thin metal walls, the cells therein having interior walls of fusible material and being filled alternately with liquid and solid reagents, which reagents generate gas under pressure when mixed, and fusible plugs in the exterior cell walls arranged to burst under heat and pressure on generation of gas within the extinguisher.

6. A fire extinguisher of narrow rectangular form comprising thin metal walls of high heat conductivity, the interior walls being of low tem-

perature fusible material providing a plurality of cells, said cells being alternately filled with liquid and solid reagents for generating flame-extinguishing gas on intermixture with each other.

5 7. A fire extinguisher comprising an envelope filled with solid, and capsules packed in the solid and containing reagent adapted to evolve fire-smothering gas when contacted with the solid, the capsule walls being adapted to release their reagent on being heated, and the envelope walls being adapted to rupture on the formation of gas, whereby flame-smothering gas is spread over a flame.

15 8. A fire extinguisher comprising an envelope with interior cellular structure, the cell units having low fusing wall portions and containing reagents to generate fire-smothering gas upon contact with each other, the envelope having spaced fusible portions adapted to be dislodged under the influence of temperature higher than that effective on the interior structure, by gas pressure generated within the envelope.

20 9. A fire extinguisher comprising an envelope of heat conducting materials having ports with closures adapted to be blown out under the combined influence of heat and gas pressure within the envelope, and reagents within the container separated by walls of fusible material, capable of combining upon the fusion of said walls to produce flame extinguishing gas under pressure within the envelope.
